UNITED STATES PATENT OFFICE.

CHARLES W. BROWN, OF NEWTON, MASSACHUSETTS.

WOVEN-WIRE MATTRESS.

SPECIFICATION forming part of Letters Patent No. 357,697, dated February 15, 1887.

Application filed February 1, 1886. Serial No. 190,433. (No model.)

To all whom it may concern:

Be it known that I, CHARLES W. BROWN, of Newton, county of Middlesex, and State of Massachusetts, have invented an Improvement 5 in Woven-Wire Mattresses, of which the following description, in connection with the accompanying drawing, is a specification, like letters on the drawings representing like parts.

This invention relates to woven-wire mattresses, and has for its object to prevent sagging of the same when supporting persons of unequal weight, the mattress at the same time preserving its elasticity.

Woven-wire mattresses have been to a great 15 degree objectionable on account of sagging when supporting persons of unequal weights, said sagging causing the occupants of the bed to roll toward the center.

Prior to my invention woven-wire fabrics 20 employed in mattresses have been supported upon spiral springs, one end of each of said springs being fastened to the wire mattress, the said springs having their other ends secured to bars or slats, which in turn have 25 their ends fastened to the side and end rails of the frame-work by springs. Such construction prevents the sagging of the mattress, but it also at the same time deprives the wire fabric of the greater part of its elasticity.

Wire bands or springs placed beneath and 30 in contact with the wire fabric have been used, said bands or springs being extended diagonally across the wire mattress and crossing each other in the center. The bands or springs referred to, while supporting the mattress at the 35 center, do not prevent sagging or rolling toward the sides when the said mattress supports two persons, such mattress being especially adapted to support only one person.

In order to prevent the sagging toward the 40 center of the wire mattress when supporting two persons of unequal weight, and at the same time preserve to the wire mattress all its elasticity, I have secured to the side pieces of the 45 mattress-frame one or more transverse bands and a series of oppositely-converging and overlapping bands attached to the end pieces of said mattress-frame, said bands being located below and, for the greater part of their 50 length, out of contact with the wire.

The drawing shows in plan view the under side of a woven-wire mattress, showing my invention applied thereto, only a part of the wire fabric being shown.

The mattress-frame, consisting of the end 55 pieces, a a' , and side pieces, a^2 a^3 , and provided with the woven-wire fabric A, attached thereto, may be of usual or preferred construction.

In connection with the woven-wire mattress 60 I provide a metallic band, c , having, preferably, at each end a coiled spring, c' , the said band being attached by its springs to the side pieces, a^2 a^3 , about midway of their length, to provide at or about the middle of the mattress 65 a transverse band, which, for convenience, I term the "main" or "primary" band.

In addition to the transverse bands c , I also provide the longitudinal bands d d e e , the former of which, preferably a pair, being secured to the end piece a near its ends, and then converging and being attached to the short strip or band d' , which in turn is provided with a coiled spring, d' , secured to the end piece a' , at or about its center. The 70 other longitudinal bands, e e , are each provided at one end with coiled springs e' , which in turn are secured to the end piece a' near its ends, the said longitudinal bands e then converging in an opposite direction to the convergence of the bands d , and being attached to the single strip e' , which in turn is attached to the end piece a at or about its center, all as clearly shown in the drawing.

The bands d and e are interposed between 85 the woven fabric A and the transverse band c , and are out of contact with said fabric except where they are fastened to the end piece, a , as shown in the drawing. By this arrangement it will be noted that the oppositely-converging 90 longitudinal bands d and e overlap each other and cross the transverse or main band c , preferably at two points about equidistant from each other and from the side pieces, a^2 a^3 , so that when the woven-wire fabric A is strained 95 or caused to sag by reason of weight thereon, the said fabric by said weight is brought in contact with the bands d and e . As the woven fabric comes in contact with the bands d and e , the strain upon said fabric is transferred 100

from it to one or more of said bands, and, by reason of the arrangement of said bands, the strain or pressure is distributed throughout and borne by all or nearly all of said bands, thereby equalizing the pressure, and, in substance, preserving the woven-wire mattress in its normally level or flat condition.

Whenever strain is exerted on the mattress fabric at or about or substantially in the line 10 of the transverse band *c*, and one side of the longitudinal center of the mattress - frame, which is usually the case where two persons occupy the bed, such strain is directly transmitted from the mattress fabric to the overlapping bands *d e*, and in turn to the transverse band *c*, at the point where said bands cross each other, to thoroughly equalize the strain, and, in effect, spread such strain throughout the mattress fabric. The bands *d* and *e* 20 being below and out of contact with the woven fabric of the mattress preserves to said woven fabric its elasticity, while at the same time they prevent sagging of said fabric when the latter is brought in contact with them.

25 The coiled springs enable the bands to give more or less, as may be necessary, when strain or pressure is applied to the woven-wire mattress.

It will be noticed that the transverse band 30 *c* and overlapping bands *d e* are crossed or grouped at two main points—namely, in the line of the transverse band and one point to each side of the longitudinal center of the frame—which points of grouping of the bands 35 are located at the two places of the mattress fabric which, in the ordinary use of the bed,

receive the largest portion of the weight of the persons occupying said bed, and consequently are subjected to the greatest strain. By such arrangement of the bands sagging of the mattress fabric at such point is prevented, and all rolling toward the center by reason of the unequal weights of the persons occupying the bed is obviated.

I claim—

1. A frame for bed-bottoms provided with an attached woven-wire fabric, combined with a transverse band connected to the side pieces of the frame, and the pairs of oppositely-converging bands extending from end to end of the frame, and connected to the ends of said frame and overlying the transverse band, the said several bands underlying the wire fabric, all substantially as described.

2. A mattress-frame having side and end pieces and provided with the woven-wire fabric, a transverse band having at its ends coiled springs secured to the side pieces of the frame, the oppositely-converging overlapping bands secured at their points of convergence to metallic strips, and coiled springs interposed between said longitudinal bands and the mattress-frame, all combined substantially as described.

In testimony whereof I have signed my name 65 to this specification in the presence of two subscribing witnesses.

CHAS. W. BROWN.
